GRATE BAR

Adolph E. Binder, Spokane, Wash.

Application October 27, 1933, Serial No. 695,497

3 Claims. (Cl. 126—168)

My invention relates to grate bars and certain objects of the invention are to provide a grate bar comprising novel head supports, a novel grate bar frame supported by the head supports in such manner as to allow for expansion and contraction, a plurality of grate bar sections supported in a novel angular manner by the grate bar frame for the purpose of minimizing warpage of the bars, and to provide reinforcements and means for maximum circulation of air through the frame and under the grate bar sections. Further objects are to provide a grate bar that is durable and which may be readily assembled and taken apart.

With the above and other objects in view which will appear as the description proceeds, the invention consists of the novel construction, adaptation, combination and arrangement of parts hereinafter described and claimed. These objects are accomplished by devices illustrated in the accompanying drawing; wherein:

Figure 1 is a view in perspective of the grate bar as a whole; Fig. 2 is a detail view in perspective of a head support for the grate bar frame; Fig. 3 is a fragmentary view in side elevation showing an end of the grate bar frame in section and resting on a head support; Fig. 4 is a view in side elevation of the grate bar frame with grate bar sections seated thereon; Fig. 5 is a detail view in inverted perspective showing an end grate bar section; and Fig. 6 is a corresponding view showing an intermediate grate bar section.

Referring to the drawing throughout which like reference numerals indicate like parts, the numeral 5 designates an angle iron sill which is ordinarily fixed around the fire brick sides of a furnace fire box. The numeral 6 designates a head support, it being understood one of said supports is used at each end of the device. Said head support is bifurcated to form a pair of outwardly projecting legs 7 which rest on the sill 5 and are grooved or cut away on their undersides, as at 8, for the entry of air. A depending flange 9 is formed on the inner end of said head support and a round top shoulder 10 projects from the upper portion of said flange and terminates in a slanting head 11.

The grate bar frame is a casting comprising sides 12 and ends 13, and the sides are preferably strengthened by transverse integral partitions 14. The ends are provided with semi-angular recesses 15 cut in from their bottom edges. These recesses fit onto the shoulders 10 of the head supports 6 leaving sufficient space for longi-

tudinal expansion and contraction of the grate frame between the flange 9 and the slanting head 11 as clearly shown at 16 in Fig. 3 of the drawing.

The top edges of the grate bar frame sides 12 are formed in saw-tooth fashion to provide angular depressions 17 and angular projections 18. Said angular depressions and projections are not transversely opposite each other but are respectively offset from each other as clearly shown in Figs. 1 and 4. In other words, lines from the same points of the depressions and projections on one side extending to corresponding points of said depressions and projections on the other side are not normal to the sides and slant with respect to the right angular ends 13 of the grate bar frame. This is one important feature of the invention. The points of the angular projections 18 are cut off to form short flat portions 19 for reasons hereinafter set forth. The bottom edges 20 of the sides 12 of the grate bar frame may be convex or curved downwardly although this is a matter of choice.

The grate bar sections, an end one of which is shown in Fig. 5 and an intermediate one shown in Fig. 6, are castings comprising sides 20 and bars 21 which diagonal bars project outwardly beyond the sides and are disposed at the same slant with respect to said sides as are the depressions 17 and projections 18 respectively on opposite sides of the frame sides 12, as hereinbefore set forth in detail. The sides 20 of the grate bar sections are disposed the same distance apart as are the sides 12 of the grate bar frame, and said sides 20 are extended down to form depending truncated V-shaped projections 22 whose points are cut off as shown at 23 to provide short flat ends. The central diagonal bar of each section extends all the way down to the bottoms of the projections 22 of the sides 20 thus forming partitions 24. On each side and intermediate of the central and end bars 21 of each section another diagonal bar is extended down below the sides to form depending fins 25.

The depending truncated V-shaped projections 22 of the grate bar sections terminate short of the ends of the sides 20 thus leaving flat surface portions 26 at the ends of the grate sections. The sides 20 of the sections, being the same distance apart as are the sides 12 of the frame, the depending truncated V-shaped projections 22 of the sections fit into the V-shaped depressions 17 of the frame sides 12. Said projections, being more obtuse than said depressions, the flat end portions 26 of the sections rest on the flat surfaces 55

19 of the frame projections 18. This arrangement leaves spaces 27 between said depressions and projections for the entry of air, and the upper edges of the frame sides are beveled to facilitate the entry of air through these spaces. An end bar 21 of the end grate sections is cut away at 28 to also permit the entry of air as shown in Fig. 5. Said end bar may merge into the next bar 21, as shown at 29, for the purpose of making a rectangular end on the outside of the end grate sections so that they will fit snugly against the end flange 9 of the head support 6 as shown in Fig. 1.

It will now be apparent that I have provided a grate bar that is durable, which may be readily assembled and taken apart, which allows for ample circulation of air, and which is amply reinforced against warping. Having thus described my invention, it being understood that minor changes may be resorted to in its construction without departing from the scope and spirit of the invention, what I claim and desire to secure by Letters Patent of the United States is:—

1. A grate bar comprising head supports, a grate bar frame supported by the head supports, the upper edges of the frame having V-shaped depressions therein, a plurality of grate bar sections supported by the frame, said sections having depending V-shaped projections that fit into

the depressions of the frame, and said projections being more obtuse than the depressions whereby spaces are left between the projections and depressions.

2. A grate bar section comprising sides with depending V-shaped projections, a plurality of parallel bars disposed in diagonal relation with respect to the sides, the central bar extended to the bottom of the depending V-shaped projections to form a partition, and a bar on each side 10 of the partition extended below the depending V-shaped projections to form depending fins.

3. A grate bar comprising head supports, a grate bar frame supported by the head supports and consisting of rectangular sides and ends, the 15 top edges of the sides having V-shaped depressions with short flat portions therebetween, the opposing depressions of the respective sides being offset from each other longitudinally of the frame, and a plurality of grate bar sections comprising diagonal bars and depending sides having truncated V-shaped projections adapted to be mounted on said frame with said depending sides fitting in said depressions and leaving air circulating spaces between the bottom of said depressions and the truncated ends of said depending sides.

ADOLPH E. BINDER.
